NONREFILLABLE BOTTLE STOPPER

Edgeworth Greene, Upper Montclair, N. J.

Application March 30, 1935, Serial No. 13,801

4 Claims. (Cl. 215—14)

This invention relates to improvements in bottle stopper assemblies and more particularly to improvements in bottle stopper assemblies of the non-refillable type.

5 An object of the invention is to provide in a bottle stopper assembly of the foregoing character, means to prevent relative rotation between the parts in their assembled condition.

Another object of the invention is to provide 10 means on the top of the bottle neck for engaging the sealing gasket of the assembly in such fashion as to prevent rotation of the gasket relative to the bottle.

A further object of the invention is to provide 15 means on the cover member of the assembly for engaging the gasket of the assembly in such fashion as to prevent relative rotation between the cover member and the gasket.

A still further object of the invention is to 20 provide means formed integrally with the valve casing of the assembly for engagement with the gasket of the assembly in such fashion as to prevent relative rotation therebetween.

In carrying out the objects and purposes of the 25 present invention, the assembly comprises a bottle, a valve casing fitting within the bottle and having an external flange overlying the top of the bottle, a gasket overlying the top of the bottle neck, a cover member engaging the valve casing 30 and contacting with the gasket, and an attaching member for securing these parts to the bottle, such attaching member, in the preferred form, being a ferrule engaging a part of the cover and being locked to the exterior wall of the bottle. In 35 order that the parts of the assembly may be held rigidly against rotation with respect one to another, provision is made for preventing such rotation. In the form of the invention shown, the valve casing, a part of which fits inside of the 40 bottle neck, is provided with an external flange to overlie a part of the top surface of the bottle neck. This flange, however, is of such diameter as to leave a portion of the top surface of the bottle neck uncovered. The valve casing has as 45 sociated therewith an annular gasket member of such diameters, internal and external, as to substantially completely cover the top of the bottle neck. The cover member is provided with means for engaging the valve casing in such fashion as to normally secure these two parts together, and this cover member also has a bottom portion of 50 suitable size to overlie the gasket and flange when these parts are positioned on top of the bottle neck.

55 When the parts of the stopper are assembled

in proper relation to the bottle, they are held in assembled condition by means of a ferrule, part of which overlies an outer surface of the cover, and another part of which is spun into engaging relation with the outer wall of the bottle neck. 5 To prevent rotation between the parts of the stopper and the bottle neck, the invention contemplates, in the first instance, the provision of some means formed integrally with the top surface of the bottle neck to engage the gasket in 10 such fashion as to prevent relative rotation between the gasket and the bottle neck. Since the cover member is preferably made of glass, ceramic material, metal, or any other suitable material, it is possible that the gasket engaging surface of this cover may be left unglazed or so roughened that this surface will contact with the top surface of the gasket with such gripping action as to prevent rotation between the cover member and the gasket. If additional locking 15 action between the cover member and the gasket is desired, this cover member may be provided with integral formations of such character as to positively grip the gasket sufficiently to prevent 20 undesired relative rotation between these parts. As a final rotation preventing measure, the invention contemplates the provision of some formation integral with the flange of the valve casing for engagement with the gasket in such fashion as to positively prevent rotation between 25 these parts. The various formations for preventing rotation may be used in any desired combinations, it being understood that the primary requirement in each instance is that rotation between the gasket and the bottle neck is to be prevented, since the friction between the other parts 30 in their normal form will, in ordinary circumstances, lock these parts together sufficiently for 35 the purposes desired.

Other features, objects and advantages of the 40 invention will become apparent by reference to the following detailed description of the accompanying drawing, wherein—

Fig. 1 is a vertical section of a bottle and stopper assembly showing a form of the invention. 45

Fig. 2 is a plan view, partially in section, of the same assembly.

Fig. 3 is a section taken substantially on the line 3—3 of Fig. 2.

Fig. 4 is a perspective view of the top of a 50 bottle neck incorporating a feature of the invention.

Fig. 5 is a fragmentary vertical section of a modification of the invention.

55

Fig. 6 is a perspective view of a portion of a valve casing showing a feature of the invention.

Referring now to the drawing, 10 indicates the neck of a bottle to which is secured a stopper

5 assembly, the assembly comprising a valve casing 11, a sealing gasket 12, an orificed cover member 14 and a retaining ferrule 15. Inasmuch as these parts, per se, have been described in detail in my pending application Serial No. 8,605, filed Feb. 28, 1935, and since they broadly 10 form no part of the present invention, a detailed description thereof is omitted herein. Suffice it to say that the valve casing 11, within which is placed some suitable valve mechanism, is made 15 of metal, ceramic material or any other suitable material and is provided with an external flange 16 at the top thereof of such diameter as to overlie a part only of the top surface of the bottle neck 10. The gasket 12 is of some suitable 20 sealing material, such as cork. The orificed cover member 14 may be made of metal, glass, ceramic material, or any other material having the proper characteristics for the purpose intended. This cover member 14 is provided with depending lugs 25 17 which frictionally engage the inner wall of the valve casing, and the cover member also is provided with a bottom surface 18 shaped and sized to overlie the top of the bottle neck 10. The ferrule 15 is made of some suitable metal, 30 such as aluminum, the ferrule being attached to the assembly to hold the parts together by spinning the skirt part thereof into and over depressions and ribs on the exterior of the bottle neck. It is to be understood, of course, that the spinning 35 takes place while the parts are in the relation shown in Fig. 1, and under such pressure as to compress the gasket 12.

When the parts are assembled and locked together as shown in Fig. 1, it is desirable that 40 relative rotation between the various parts be prevented in order that the seal made by the gasket can be retained as an air-tight and liquid-tight seal, thereby to prevent undesired egress of liquid from the bottle or introduction of liquid into the bottle. When a screw cap of 45 conventional type (not shown) is used to enclose the pouring orifice of the cover member 14 it is desirable that rotation of the parts of the stopper relative to the bottle be prevented in order that the screw cap can be tightened relative to the cover member sufficiently to completely close the pouring orifice thereof, and in order that a screw cap tightly engaging the cover member can be loosened without the necessity of holding the 50 cover member. When the cover member is manufactured, the bottom surface 18 may be left unfinished, that is, more or less rough, so that this bottom surface will grip the upper surface of the gasket 12 with sufficient force as to normally prevent relative rotation between the cover member and the gasket. The top of a bottle neck may not possess sufficient roughness to prevent relative rotation between the gasket and the bottle neck if considerable torque is applied 55 to one of the members. Accordingly, in order that relative rotation between the gasket and the bottle neck be prevented, the top of the bottle neck is provided with suitable integral formations for gripping or penetrating the gasket sufficiently 60 to lock or anchor the gasket to the bottle neck. In the form shown in the drawing the formations comprise upstanding ribs 20 which are positioned diametrically opposite each other. It is to be understood, however, that while a pair of ribs 65 have been shown, under favorable conditions a

single rib will be sufficient, or if conditions warrant, the number of ribs may be increased to meet the conditions.

When the parts of the assembly are secured together in the manner shown in Fig. 1, the ribs 5 20 will penetrate the material of the gasket 12 as shown in Fig. 3, so that the gasket is anchored to the bottle neck and cannot be turned relative thereto.

If additional anchoring between the cover 10 member and the gasket beyond that normally existing is desired, the cover member may be provided with integral formations, such as shown in Fig. 5 wherein a short rib 25 extends downwardly from the bottom surface 18. This rib 25 extends radially of the cover member only a short distance, since it must lie beyond the area of the surface 18 with which the top of the flange 16 contacts. When the parts are assembled, the rib 25 penetrates the gasket 12 sufficiently to 20 anchor these two parts together. Of course, the formations may be of any desired number as in the case of the formations 20.

In order that the parts be locked together against rotation still further, the flange 16 of the 25 valve casing may be provided with dents or depressions 30 which will engage the material of the gasket 12 when the parts are assembled to anchor the valve casing against rotation relative to the gasket. The flange 16 may have its outer 30 edge shaped otherwise than shown. For example, the outer edge of the flange might be elliptical instead of circular, with the result that when the flange is pressed into the gasket, relative rotation between these parts will be substantially prevented. Also, the exterior of the bottle neck 35 may be shaped to prevent rotation of the ferrule therearound.

From the foregoing it will be seen that the present invention provides efficient means for 40 securing a bottle stopper assembly to a bottle neck in such fashion that relative rotation between the parts themselves or between the parts and the bottle neck is prevented. The provision of surface irregularities on the contacting parts 45 causes the parts to so frictionally engage each other, that, for all practical purposes, rotation of one part relative to another is prevented. While the irregularities in the surfaces of the parts have been illustrated as being in the nature of definite 50 ribs and the like, it is contemplated that these surfaces may be so formed as to have sufficient roughness as to set up the necessary friction between the parts for the purpose explained. For example, the top of the bottle neck may be formed 55 in a manner similar to unglazed porcelain, that is with minute surface irregularities instead of definite spaced ribs. Moreover, where the valve casing is made of some ceramic material the flange of this casing can be left unglazed so that 60 a good frictional contact will be made, both with the cover member and with the gasket. Also, since the lugs of the cover member engage the valve casing with a press fit as shown, it will be apparent that relative rotation between the cover 65 member and the valve casing is substantially prevented. The upstanding ribs may, if desired, be replaced by indentations in the surfaces of the various parts without effecting any material change in results, since these desired results can 70 be obtained either by formations forced into the material of the gasket or by the material of the gasket being forced into formations on the members with which it contacts.

It is to be understood that various combina- 75

tions of anchoring means may be utilized within the contemplation of this invention, and further that the invention is not limited to any particular form of integral formations as described, since 5 various formations may be utilized with equal efficiency. The primary requirement for preventing undesired rotation between the parts is that means be provided to positively prevent relative rotation between the sealing gasket and the 10 bottle neck. However, if positive assurance of rotation prevention is desired, use may be made of either the surface irregularities on the cover member with the surface irregularities on the bottle neck, or, the surface irregularities on the 15 valve casing flange with the surface irregularities on the neck, or, use may be made of a combination of all three types of surface irregularities.

I claim:

- 20 1. The combination of a bottle and a stopper assembly secured thereto, said stopper assembly comprising a flanged valve casing, a cover member, and a sealing gasket compressed between the top of said bottle neck and the flange of said valve casing and said cover member, the top of said bottle neck being provided with integral anchoring means for so gripping said gasket as to prevent relative rotation between the gasket and the bottle, the bottom of said cover member being in such frictional contact with said gasket as to normally prevent relative rotation between the cover member and the gasket.
- 25 2. The combination of a bottle and a stopper assembly secured thereto, said stopper assembly comprising a flanged valve casing, a cover member and a sealing gasket compressed between the top of said bottle neck and the flange of said valve casing and said cover member, the top of said bottle neck being provided with integral engaging means for so gripping said gasket as to

prevent relative rotation between the gasket and the bottle, and anchoring means formed on the bottom of said cover member for so gripping said gasket as to prevent relative rotation between the cover member and the gasket.

5

3. The combination of a bottle and a stopper assembly secured thereto, said stopper assembly comprising a flanged valve casing, a cover member and a sealing gasket compressed between the top of said bottle neck and the flange of said valve casing and said cover member, the top of said bottle neck being provided with integral anchoring means for so gripping said gasket as to prevent relative rotation between the gasket and the bottle, anchoring means formed on the bottom of 10 said cover member for so gripping said gasket as to prevent relative rotation between the cover member and the gasket, and anchoring means formed integrally with the flange of said valve casing for so gripping said gasket as to prevent 15 relative rotation between the gasket and the valve casing.

20

4. The combination of a bottle and a stopper assembly secured thereto, said stopper assembly comprising a valve casing having a flange partially overlying the top of said bottle neck, a cover 25 member and a sealing gasket compressed between the top of the bottle neck and said flange and said cover member, anchoring means formed integrally with the top of said bottle neck for so gripping said gasket as to prevent relative rotation 30 between the gasket and the bottle neck, and anchoring means formed integrally with the bottom of said cover member for so gripping said gasket as to prevent relative rotation between the gasket and the cover member, said last mentioned anchoring means being positioned outside the area of the bottle neck overlapped by said flange.
